ATTORNEY.

UNITED STATES PATENT OFFICE.

MANSFIELD H. DOTSON, OF BALTIMORE, MARYLAND.

OYSTER-PACKAGE.

SPECIFICATION forming part of Letters Patent No. 374,119, dated November 29, 1887.

Application filed September 29, 1887. Serial No. 250,993. (No mode.)

To all whom it may concern:

Be it known that I, MANSFIELD H. DOTSON, a citizen of the United States, residing at Baltimore, in the State of Maryland, have invented 5 certain new and useful Improvements in Oyster-Packages, of which the following is a specification.

My invention relates to the construction of a package for the transportation of raw oysters, and is illustrated in the accompanying drawings, in which—

Figure 1 is a side view of the package. Fig. 2 is a top view. Fig. 3 is a vertical section of the package. Figs. 4 and 5 are views of the 15 cross-bar for the cover.

The letter A designates the sides of the package, which is cylindric or barrel shape and made of ordinary staves.

b is the bottom head, which has its edge or 2c rim chamfered and fitted in a croze, as at e, in the usual manner, leaving a chine, d. A second or double bottom head, e, is on the outside against the chamfered head b, to which it is secured, and is fitted close within the said chine 25 d, and its surface is flush with the ends of the staves. The grain of the wood of the outside head runs in a transverse direction from the grain of the chamfered head. This construction of bottom head gives stability and prevents the weight of the contents of package 30 from coming entirely on the rim of the chamfered head.

The cover-head is composed of two thicknesses of wood, the inside, f, which fits into 35 the chine d', and the outside, g, which is larger and whose edge forms a flange, g', which projects beyond the inside thickness and rests upon the top ends of the staves. The grain of the two thicknesses composing the cover-head 40 extends transversely with respect to each other. To the cover-head on the outside is attached a diametrical bar, I, provided at each end with a bolt-socket, k, and having a swell curved surface, l, between the two end sockets, 45 as shown in Fig. 4, which is in contact with the outside thickness of the cover-head. This bar I, having the swell curved surface l, has the effect to warp or bulge the cover, so that the

flange at the two points l', located on a diametrical line extending in a direction transverse with respect to the length of said bar, will be more prominent and first bear on the ends of the staves, and then when the socket ends k of the bar are pressed down hard the effect will be to spring the bar and cover-head, 55 so as to cause the flange g' all around the rim to rest in close contact with the ends of the staves. Two bolts, m, are secured to the outside package at diametrical opposite sides, and their threaded ends project beyond the ends of 60 the top chine, d', and when the cover-head is in place these ends occupy the end sockets, k, of the bar I. By having the bolts secured to the outside of the package the flange g' of the cover adjoining the bolts is not cut away, as 65 would be the case if the bolts were on the inside. A nut, n, on each bolt presses the bar I down hard and brings the flange g' in close contact with the stave ends. Each bolt has a hole, o, and the wire of a lead seal, p, passes 70 through the said hole and serves to seal the parts and prevent the removal of the cover-head by an unauthorized person without the fact of removal being known.

A package having the features here described 75 may be made of any size, ranging from five to forty gallons, and will serve for the safe transportation of raw oysters or any other commodity.

Having described my invention, I claim and 80 desire to secure by Letters Patent of the United States—

A package of cylindric shape having two bolts, m, secured at the outside, a cover-head whose rim g' rests upon the top edge of the 85 package-wall, a bar, I, provided at each end with a bolt-socket, k, and between said ends having a swell curved surface, l, secured in contact with the outside of the cover-head, and nuts on the bolts, as set forth.

In testimony whereof I affix my signature in the presence of two witnesses.

MANSFIELD H. DOTSON.
